COMBINED AUTOMOBILE STEERING WHEEL AND HORN CONTROL DEVICE

Filed Feb. 19, 1937

Inventor:
Robert D. Snoke
By Fred Gerlach Atty.

UNITED STATES PATENT OFFICE

107,459

DESIGN FOR A COMBINED AUTOMOBILE STEERING WHEEL AND HORN CONTROL DEVICE

Robert D. Snoke, South Bend, Ind., assignor to
Auburn Automobile Company, Connersville,
Ind., a corporation of Indiana

Application February 19, 1937, Serial No. 67,743

Term of patent 7 years

To all whom it may concern:

Be it known that I, Robert D. Snoke, a citizen of the United States, residing at South Bend, in the county of St. Joseph and State of Indiana, have invented a new, original, and ornamental Design for a Combined Automobile Steering Wheel and Horn Control Device, of which the following is a specification, reference being had to the accompanying drawing, forming a part thereof.

Figure 1 of the drawing is a top perspective view of a combined automobile steering wheel and horn control device, showing my new design; and

Figures 2 and 3 are plan and side views respectively of the combined wheel and horn control device, showing my new design.

The characteristic features of my new design reside in the horn control device shown in full lines.

I claim:

The ornamental design for a combined automobile steering wheel and horn control device substantially as shown and described.

ROBERT D. SNOKE.
